UNITED STATES PATENT OFFICE.

JOHN JOHNSON, OF BATON ROUGE, LOUISIANA.

SAFETY-CATCH FOR BREASTPINS.

SPECIFICATION forming part of Letters Patent No. 378,054, dated February 14, 1888.

Application filed August 2, 1887. Serial No. 245,916. (No model.)

To all whom it may concern:

Be it known that I, JOHN JOHNSON, of Baton Rouge, in the parish of East Baton Rouge and State of Louisiana, have invented certain new and useful Improvements in Safety-Catches for Breastpins, &c., of which the following is a specification.

This invention relates to an improved catch for breastpins and similar articles; and it consists of a breastpin provided with a safety-catch composed of a fixed and slotted socket for the entrance of the pin-tongue, and a sliding and spring-actuated socket guided on the fixed socket, and suitable stops for confining the motion of the sliding socket within certain limits, so as to permit the removing and inserting of the point of the pin-tongue in or from the fixed socket when the sliding socket is moved back so as to clear the fixed socket, as will appear more fully hereinafter, and finally be pointed out in the claims.

In the accompanying drawings, Figure 1 represents a breastpin with my improved safety-catch. Fig. 2 represents a vertical longitudinal section through the safety-catch. Fig. 3 is a side elevation of the same, partly in section through the movable sleeve; and Figs. 4 and 5 are respectively a vertical and a horizontal section of a modified form of the safety-catch for breastpins.

Similar letters of reference indicate corresponding parts.

Referring to the drawings, A represents the base-plate of a breastpin or other article of jewelry, near one end of which is hinged the pin-tongue B by any approved hinge-connection, while a safety-catch, C, for the point of the pin-tongue is applied near the other end.

The safety-catch C is composed of a fixed socket, b, that is applied to a fixed post, a, of the base-plate A, said post and socket being recessed at one side for the insertion of the point of the pin-tongue B. The fixed socket b is of less diameter than the post a, and serves to guide a movable socket, d, on the same, which socket is pressed by a spiral spring, d', toward the collar or stop formed by the post a, around the fixed socket b. The spiral spring d' is located between the inwardly-extending flange d² of the sliding socket d and the head e' of a screw-plug, e, that is inserted into the outer end of the fixed barrel or socket b, as shown in Figs. 2 and 3; or the spring d' is inserted into a separate socket, d³, attached to

the base-plate A, as shown in Figs. 4 and 5. 55 In one case the sliding and spring-actuated socket d is stopped in one direction by the post a, and in the opposite direction by the head of the screw-plug e, while in the other case the sliding socket d is stopped in one direction by the post a and in the opposite direction by the socket d³. The sliding socket d is provided with an exterior rim, d', for being conveniently taken hold of.

When it is desired to open the pin-tongue— 65 that is to say, remove it from the fixed socket b and post a—the sliding sleeve d is taken hold of and pushed back until it clears the slot of the fixed socket, so that the point of the pin-tongue may be removed therefrom. For 70 closing the breastpin, the socket is pushed back clear of the recess of the fixed barrel, so that the pin-tongue can be inserted, after which the sliding socket is moved over the fixed socket by the spring, so as to prevent the escape of the pin-tongue from its catch. 75

Having thus described my invention, I claim as new and desire to secure by Letters Patent—

1. In breastpins and similar articles, the combination, with a base-plate, a pin-tongue 80 hinged thereon, a fixed post, a fixed socket attached thereto, said socket and post being provided with a recess for inserting the point of the pin-tongue, a sliding socket guided on the fixed socket, a spring acting on the sliding socket and pressing the same over the fixed socket, and means, substantially as described, for stopping the sliding socket in either direction, so as to permit either the releasing or inserting of the point of the pin- 85 tongue, substantially as set forth.

2. In breastpins and similar articles, the combination, with a base-plate and hinged pin-tongue, of a fixed post, a fixed socket attached thereto, said post and socket having a recess 95 for the point of the pin-tongue, a sliding and spring-actuated socket guided on the fixed socket, said socket having an inwardly-bent flange at one end, and a screw-stud having an enlarged head, inserted into the outer end of the fixed socket, substantially as set forth.

In testimony that I claim the foregoing as my invention I have signed my name in presence of two subscribing witnesses

JOHN JOHNSON.
